Atty.

UNITED STATES PATENT OFFICE.

JOHN W. LESLIE, OF EVANSTON, ILLINOIS.

REINFORCING GIRTH.

Application filed March 15, 1920. Serial No. 365,951.

To all whom it may concern:

Be it known that I, JOHN W. LESLIE, a citizen of the United States, residing at Evanston, in the county of Cook, State of Illinois, have invented an Improvement in Reenforcing Girths, of which the following is a specification.

This invention relates to reenforcing girths for use in forming joints in metallic tensional binders, known as "box strap," or the like; and has for its object the production of a girth of simple and economical construction, having among others the advantages in application and use, hereinafter 10 more specifically pointed out.

In the drawings, which constitute merely an illustrative embodiment of the invention:

Fig. 1 is a perspective view, partly in 20 cross section, showing my new reenforcing girth in process of being applied to mutually overlapped strap ends,

Fig. 2 is a cross sectional view showing 25 the girth as applied to said strap ends, prior to the joint forming operation proper,

Fig. 3 is a view similar to Fig. 2, showing the girth at a succeeding stage in the process of forming a joint,

Fig. 4 is a side elevation of a joint formed 30 with my reenforcing girth,

Fig. 5 is a plan view of the joint,

Fig. 6 is a cross sectional view on lines 6-6 of Fig. 4, and

Fig. 7 is an elevation of a box with a 35 binder applied thereabout in a manner to illustrate a method of application forming a part of my invention.

In the drawings a box strap surrounding a box or package is shown, having a lower 40 end 1 and an upper end 2 superposed upon and in alignment with the lower end. The box strap is represented in the position it assumes when taken from a reel and applied about a box or package, part of which is 45 shown in dotted lines in Fig. 1. The disclosure further shows the manner of application of my new girth and a resulting illustrative joint, as will be described.

The reenforcing girth of my invention 50 comprises a back piece 3 shaped to conform with and lie flat upon the top surface of the top strap end 2; and of appropriate dimensions. The back piece 3 is provided at one longitudinal edge with a flange 4 bent substantially at right angles with the flange 3, and adapted to abut and lie snugly against

the flush longitudinal edges 5 of the overlapped strap lengths. Integrally formed with the flange 4, extending inwardly therefrom and forming a slightly obtuse angle therewith is the flange 6, the construction being such that a hook is formed by the parts 3, 4, and 6, having a slightly flaring mouth, by means of which one side of the girth may be hooked sidewise under the overlapped strap lengths in the manner clearly shown in Figures 1 and 2.

Opposite the hook 4-6 on the back piece 3 is the integrally formed outwardly and downwardly extending flange 7, prolonged into a recurved flange 8, extending inwardly and upwardly toward the inner surface of the back piece 3 and having a rounded outer surface. The flange 8 terminates in an edge 9, which is located inwardly beyond the angle 10 between the back piece 3 and the flange 7.

In applying a girth of the character hereinabove described it is unnecessary to thread the same successively upon two overlapped strap ends as is the case with girths of slotted tubular construction, heretofore widely in use or to perform bending operations upon the girth in the process of applying it in embracing relation upon overlapped strap lengths. Assuming that the strap is applied about the box or package with a mutual overlap, as indicated in Figure 1, the girth of my invention may be applied thereto hooking the flange 6 under the overlap in the strap, thereby bringing the girth into the position shown in Figure 1. Thereafter by pressing down upon the corner or angle 10, (since the girth is preferably made of metal, having at least some resiliency) the rounded under surface of the flange 8 will cam over the adjacent edge of the strap overlap (Figures 1 and 2), causing the edge 9 of the girth yieldingly to ride over the flush strap edges and to snap in under the left hand strap edge into the position shown in Figure 2. In this position of the parts the girth substantially embraces the overlapped strap and cannot fall or be shaken off.

Although the engagement of the left hand flange (Figure 2) with the strap is not complete after the foregoing operation, the girth of my invention may be brought easily into complete superficial contact with the strap in the succeeding normal operation of forming a joint in the strap and

girth by simultaneously crimping the same.

No change is necessary to accomplish this result on the right (Figure 2) since the parts 3, 4, and 6 already more or less tightly engage the strap. On the left (Figure 2) the edges 9 and the flanges 8 and 7, are so situated that compression thereupon either horizontally toward the center of the strap on the flange 7, or applied upwardly upon 10 the lowest point of the flange 8, will cause the edge 9 to move inwardly along the under surface of the flat strap 1, straightening out as it moves until the parts come into the position shown in Figure 3. In this figure 15 the girth although applied to both strap ends simultaneously, as would be impossible with a slotted tubular girth of familiar construction, has been transformed by ordinary compression incident to a crimping operation 20 into such a girth.

In Figures 4, 5, and 6, I have shown a joint formed in the overlapped strap and girth simultaneously involving edgewise crimping thereof. In forming such a joint 25 (which is selected for illustrative purposes) the region of the strap and enclosing girth is necessarily subjected to compression both inwardly, horizontally, and upwardly. Such compression applied to the girth of my 30 invention in the position shown in Figure 2, will first change the shape of the girth from that shown in Figure 2; into that shown in Figure 3 wherein the girth is in substantially complete tight superficial contact with the strap surfaces; or in other 35 words is equivalent to a slotted tubular girth although applied to both strap ends simultaneously as is impossible with such a girth.

The continuation of the crimping operation, (as indicated in Figures 4, 5, and 6) 40 forms the girth and embraced strap ends into a joint of the edgewise crimped character, illustrated in these figures. However, joints of other characters might equally well 45 be formed with the girth by applying the necessary crimping tools to the girth in the position as shown in Figure 2; the compressing effect of the operation necessary to distort or crimp the strap into substantially 50 any girth, resulting in the bending of the flanges 7 and 8 so as to bring the inner surface of these substantially into tight superficial contact with the surface of the strap 55 ends.

In Figure 7 I have illustrated more or less 60 diagrammatically a method of applying binders to boxes or packages which results in the saving of a considerable amount of strap and a generally increased efficiency in 65 operation. This method may be briefly described as follows.

The strap is fed off from a reel (not 70 shown) and its leading end is carried around the box and applied underneath the 75 continuous length 2 of the strap leading

back to the reel. Thereupon stretching tool 11 of any familiar character is applied to tighten or "stretch" the strap about the box with the desired tension. In this position of the parts, the end 7 lies underneath a continuous length of strap which extends all the way back to the reel. 70

In the method of applying these binders heretofore practised the strap was first cut to provide a second free end, and thereafter 75 a reenforcing girth successively threaded on the two free strap ends; the free ends then overlapped; the stretched tool applied; and lastly the joint-forming operation carried out. According to my new method the 80 stretching and joining operations are carried out before the top strap length is cut, so that all of the slack is taken out of the strap prior to cutting the same. The girth of my invention is applied simultaneously 85 to the overlapped strap lengths before, during, or after the stretching operation; and when this operation is completed the joint is formed as shown in Figure 7. Subsequently 90 the stretching tool may be disengaged from the overlapped strap and the strap left applied about the box, taut and joined in a closed loop, while still a continuous length thereof reaches back to the reel. Subsequently 95 the strap is cut close to the joint 12, at the point 13. The resulting new end is utilized for the next box as was the original end 1 for the box just strapped. This new 100 method of application results in a very considerable saving in strap, inasmuch as the entire slack is taken out of the strap prior to the severing thereof, so that only exactly 105 the quantity of strap necessary to encircle the package in stretched or tensional condition, and give the overlap necessary for 110 the desired joint, is utilized in applying the binder upon the box.

Having thus described my invention, I claim:

1. As an article of manufacture, a reenforcing girth for box strapping and the like comprising a somewhat resilient member formed with a back piece; a flange at one edge of the back piece and bent into the form of a hook adapted to be hooked over and engage an edge of a box strap, a second flange in the back piece opposite the first, extending substantially outwardly therefrom and having a recurved portion extending inwardly toward the opposite flange 115 whereby said girth may be applied to mutually overlapped box strap ends by hooking one flange thereover sidewise under the strap, and then snapping the remainder of the girth thereon by forcing the recurved flange portion past the opposite strap edges 120 in a direction substantially perpendicular to the face of the strap.

2. An article of manufacture, a reenforcing girth for box strapping and the like 130

comprising a somewhat resilient member formed with a back piece; a flange at one edge of the back piece and bent into the form of a hook and adapted to be hooked under and engage, and fit somewhat snugly upon an edge of a box strap, and a second flange opposite the first adapted yieldingly to be forced past the opposite edge, said flange being supplied with a curved strap edge 10 contacting portion to facilitate the forcing thereof past said edge.

3. A reenforcing girth for box strap joints comprising a back piece, a hook formed on one edge thereof and comprising 15 a flange bent downwardly from the hook member, having a flaring mouth to receive the edges of superposed alined box strap ends, a flange on the opposite edge of the reenforcing member having a recurved portion, convex on its exterior surface and adapted to be yieldingly forced over the edges of said box strap, whereby the reenforcing member may be applied by engaging 20 one edge of the superposed box strap ends in said hook and forcing the opposite flange of said member down over the other edge thereof.

4. The method of strapping boxes or the like which consists in feeding off from an 30 indefinite supply upon a reel or the like, a sufficient length to encircle the box or package, stretching the said length about the box or package without severing it from the supply, and with the free end overlapped 35 by another portion of the strap and with

the free strap end and the superposed continuous length, forming a joint in the strap crimping the overlapped portions together and thereafter severing the top strap adjacent the joint. 40

5. The method of placing tensioning devices about boxes or the like which consists in feeding off from an indefinite supply on a reel or spindle a sufficient length of tensioning device to encircle the box, stretching 45 the length about the box without severing it from the supply and with the free end adjacent to the body portion of the tensioning device, crimping the adjacent portions together to form a joint, thereafter severing the body portion of the tensioning device adjacent to the joint. 50

6. The method of placing tensioning devices about boxes or the like which consists in feeding off from an indefinite supply of tensioning device from a reel or the like a sufficient length to encircle the box, stretching the same length about the box without severing it from the supply and with the free end adjacent the body portion of said tensioning device, placing a sleeve about 55 said free end and adjacent body portion, forming a joint in the tensioning device by crimping the sleeve, free end of said tensioning device and adjacent body portion together and thereafter severing the body of said tensioning device adjacent to said joint. 60

In testimony whereof, I have signed my name to this specification.

JOHN W. LESLIE.
